US00D728539S

(12) **United States Design Patent**
Dubrule et al.

(10) **Patent No.:** **US D728,539 S**
(45) **Date of Patent:** **** May 5, 2015**

(54) **ROUTER**

(75) Inventors: **Craig Donald Dubrule**, Cary, NC (US);
Mahbubul Alam, San Jose, CA (US);
Hugo J. W. Vliegen, Menlo Park, CA (US); **Chandrodaya Prasad**, Santa Clara, CA (US)

(73) Assignee: **Cisco Technology, Inc.**, San Jose, CA (US)

(**) Term: **14 Years**

(21) Appl. No.: **29/416,694**

(22) Filed: **Mar. 26, 2012**

(51) LOC (10) Cl. **14-02**

(52) U.S. Cl.

USPC **D14/240**; D14/358

(57) **CLAIM**

The ornamental design for a router, as shown and described.

DESCRIPTION

FIG. 1 is a front perspective view of a first embodiment of a router showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The broken line portions illustrate environmental structure and form no part of the claimed design.

1 Claim, 5 Drawing Sheets
